(57) **CLAIM**

The ornamental design for a cup holder as shown and described.

DESCRIPTION

FIG. 1 is a top and front perspective view of a cup holder embodying the new design;

FIG. 2 is a bottom and rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines shown in the drawings illustrate portions of the cup holder that form no part of the claimed design. The shading lines shown in the drawings represent the approximate three-dimensional contour of the claimed design and are not intended to indicate surface decoration.
